UNITED STATES PATENT OFFICE.

FRANK B. HOPEWELL, OF CAMBRIDGE, MASSACHUSETTS.

DESIGN FOR A TIRE.

SPECIFICATION forming part of Design No. 27,464, dated August 3, 1897.

Application filed May 22, 1897. Serial No. 637,792. Term of patent 14 years.

To all whom it may concern:

Be it known that I, FRANK B. HOPEWELL, a citizen of the United States, and a resident of Cambridgeport, in the county of Middlesex and State of Massachusetts, have invented and produced a new and original Design for Pneumatic Tires, of which the following is a specification.

In the drawings accompanying and forming a part of this specification, Figure 1 is a perspective view of a pneumatic tire illustrating my design, and Fig. 2 is an enlarged cross-sectional view thereof.

The leading feature of my design for pneumatic tires consists in a tire having a series of parallel alternating ribs and depressions extending in the direction of the length of and at the inner circumference of the tire, the outer circumference being transversely and continuously convex.

As shown in the drawings, the inner circumference of the tire T is shown as provided with parallel alternating ribs and depressions *a b*, respectively, extending in the direction of the length of the tire and forming about one-third the external surface of the tire, the remaining surface or outer circumference being transversely and continuously convex. 25

Having fully described my invention, what I claim is— 30

The design for pneumatic tires, substantially as herein shown and described.

In testimony whereof I have signed my name to this specification in the presence of two subscribing witnesses.

FRANK B. HOPEWELL.
